UNITED STATES PATENT OFFICE

HEINRICH HENSE, OF LONDON, ENGLAND

OFFSET PRINTING-PRESS

Application filed September 15, 1930, Serial No. 481,891, and in Germany November 22, 1929.

The present invention relates to rotary-offset machines for single or multi-color work.

One of the objects of the present invention is so to arrange the various operative cylinders of an offset printing-press so that the pile of printed sheets may accumulate to a considerable height under the plate-cylinder of the machine, where the printed sheets are readily inspected by the operator of the machine without the necessity of his changing his normal operative position while attending the press.

Another object of the invention is so to arrange the delivery chain or belt that it likewise does not interfere with a clear visibility of the printed sheets delivered from the machine.

Another object of the invention is so to arrange the alignment of the plate-cylinder, the rubber offset-cylinder and the impression-cylinder that the periphery of the latter will lie tangent to a horizontal plane below that of the top-most delivered printed sheet.

A further object of the invention is to provide an offset printing-press in which the plate-cylinder, offset-cylinder and impression-cylinder are so arranged on the framework of the machine that there is provided immediately below the plate-cylinder a pile-delivery of unusual height, the said pile-delivery being in a space whose one side is defined by a vertical line that is tangent to the plate-cylinder, while the offset-cylinder is on the farther or trans side of the said plane; that is to say, there is nothing beneath the plate-cylinder except the pile-delivery and the belt or sprocket conveyor bringing the printed sheets to the said delivery. By this arrangement, it becomes possible, without unduly increasing the overall height of the printing-press to have an extremely high pile-delivery, so that the press may be operated for a much longer period without the necessity of shutting it down to remove the pile of printed sheets. At the same time, the operator of the press, without changing his position, is able to inspect both the printed sheets and the operation of the inking and moistening rollers, as well as the operation of the machine. It should be particularly

noted that in the arrangement as hereinbelow described there are no working parts beneath the plate-cylinder except the belt or chain sheet-delivery leading to the pile-delivery containing the printed sheets.

The invention is illustrated by the accompanying drawings in which Fig. 1 is a diagrammatic side elevation of a single-color offset press;

Fig. 2 is a similar view of a two-color offset press; and

Fig. 3 is an elevational end-view of the press, showing the pile delivery in which the printed sheets accumulate.

Some of the difficulties encountered with the hitherto known offset presses are that in the case of single-color machines, each cylinder of which carries one working surface only, and in which the pile delivery is fitted underneath the offset or blanket cylinder, there is only very little room for the pile delivery, as the distance between the offset cylinder and the floor is limited, so that it is only possible to have a pile delivery about 50 centimeters high. A further disadvantage of the hitherto known presses is that the printed sheet is delivered so low down that the operator is unable, without changing his position, to view the said printed sheet. In the case of multi-color offset machines a higher pile, say, about 100 to 120 centimeters high, is possible, provided the pile is arranged behind the position taken up by the operator, i. e. facing the plate cylinder. With such an arrangement the press must needs be of excessive length.

The present invention as related to rotary offset presses, particularly high speed machines, not only eliminates the disadvantages above mentioned, but also allows of the length of the machine being shortened, while the height and the width of the machine remain substantially as heretofore. By the present invention there is provided a machine of reasonable overall height which permits of an inbuilt pile where the printed sheets may accumulate. The height of the pile is one which obviates the frequent stoppages required for unloading the usual small pile and this increases the output of the ma-

chine. For example the height of the pile in a machine constructed in accordance with the present invention, may be from 100 to 120 centimeters high. Moreover the said high 5 pile delivery is in front of the operator when looking towards the plate cylinder, and he can therefore regulate the inking mechanism, and also inspect the delivered sheets without being compelled to stoop down or 10 to move out of his position.

One form of construction of the present invention is shown by way of example in the appended drawings.

Referring to Fig. 1, it will be seen that 15 the press comprises a plate cylinder 2 upon which the printing-plate (not shown) is mounted in the usual fashion. The plates thereon are damped by the dampening rollers 7.

20 Referring to Fig. 1, in which the various cylinders and rollers of the press are diagrammatically shown, the sheets to be printed are fed into the press from the feed-board 1, where they are taken up by the impression-cylinder 4 which presses them against the offset or blanket-cylinder 3 upon which a negative of the desired impression has been placed by the inked plates on the plate-cylinder 2. The latter is provided with ink from 25 the fountain 6, and is kept damp by the dampening rollers 7. The printed sheets are finally delivered to the pile of finished sheets 8.

30 In Fig. 2, there is shown an entirely analogous arrangement in which two-color work can be done. In this case the second color is provided by the plate-cylinder 10, blanket-cylinder 9 and the therewith associated fountain 6 and dampening rollers 7, 40 these two latter appurtenances being identical in construction and function with the similarly numbered parts in Fig. 1, and hence given the same numerical designation.

45 Fig. 3 is an end view showing the ink-fountain 6, the plate-cylinder 2, which is there shown being driven by the gearing 12. The belt 5 that delivers the printed sheets to the pile 8 is seen in all three figures.

50 In accordance with the present invention the entire space underneath the plate-cylinder 2 is left clear of all other constructional parts, and houses a pile of printed sheets 100 to 120 centimeters high. This is more particularly attained by placing the rotating 55 axis of the offset or blanket cylinder 3 (lying on the right hand side of the plate cylinder 2 in the drawings) above the plane containing the rotating axes of the plate-cylinder 2 and the impression-cylinder 4 (arranged on the right hand side of the offset or blanket cylinder 3 in the drawings, and that the said cylinder 4 is at the same time so arranged or located that the lower part of its periphery lies below the uppermost sheet in the pile 8,

which pile is located beneath the plate cylinder 2.

The chain or belt delivery drum 11 is arranged beneath the impression-cylinder 4 and lies so low down that the chain 5 consists of an inclined rising part *b* as well as the usual horizontal part *a*. This horizontal part *a*, of the delivery chain 5 is so arranged that it does not extend towards the right beyond the vertical plane I-II, which latter forms a tangent to the plate-cylinder 2 on the same side of plate-cylinder as the offset cylinder 3.

By this arrangement, sufficient space is gained underneath the foremost or plate-cylinder 2 to allow an inbuilt pile to be accommodated in that space, the pile being placed so conveniently that the uppermost sheet is only about 30 centimeters below the periphery of the plate-cylinder 2, so that the operator can easily examine a delivered sheet while tending the plate cylinder and allied parts.

55 It will be noted that all three cylinders are of the same diameter, and move with the same peripheral speed. The present invention lies in the way in which the cylinders are arranged, namely in that the rotational axis of the offset cylinder 3 lies above a plane that is defined by a line passing through the center of the rotational axes of the cylinders 2 and 4. This relationship is brought out in Figs. 1 and 2 by the broken line passing through the central axis of the said latter cylinders. It will be noticed that the axis 60 of cylinder 3 is considerable above this plane. The belt or chain that transports the sheets from the impression-cylinder 4 to the pile 8 passes over the cylinder 11, thence traveling to the left in a slanting upward direction 65 (indicated by the portion *b*), and deposits the sheets when it has reached the horizontal portion *a*. By this arrangement it is possible to have a high enough pile-delivery so that the operator of the press can examine a delivered printed sheet without stooping down as was necessary with the older types of offset press construction.

70 For the sake of clarity, only sufficient parts of the press to enable an understanding of the present invention are shown on the drawings, hence mechanical means for supporting the belt or chain 5 are not shown except in so far as the location of the vertical plane I-II requires. This plane is tangential to the periphery of the plate-cylinder 2.

75 What is claimed as new is:

1. In an offset printing-press the combination of a printing-cylinder, offset-cylinder, impression-cylinder, sheet-delivery, pile-delivery, and a frame for supporting the said cylinders, the said cylinders and pile-delivery being so disposed that the rotating axis of the offset-cylinder lies on that side of a plane containing the rotating axes of the 80

plate-cylinder and impression-cylinder that is remote from the pile-delivery, whereby the pile-delivery thus is situated immediately below said plate-cylinder, one side of the space in which said pile-delivery is located being defined by a vertical plane that is tangent to the plate-cylinder at the side where it contacts with the offset-cylinder, so that the space housing the pile-delivery is free from all working parts except the sheet-delivery.

2. In an offset printing-press the improvement which comprises the combination of a frame, a printing-cylinder, offset-cylinder and impression-cylinder, a delivery mechanism for printed sheets, and a pile-delivery so arranged that the pile-delivery lies on one side of a plane which passes through the rotating axes of the plate-cylinder and impression-cylinder while the rotating axis of the offset-cylinder lies on the opposite side of said plane, whereby the pile-delivery is located in a space which is defined by a vertical plane passing tangent to the plate-cylinder on the side where it contacts with the impression-cylinder, the periphery of the impression-cylinder lying on the plane which is below the topmost plane of the space housing the pile-delivery, there being no intermediate working parts between the pile-delivery and the plate-cylinder.

3. In an offset printing-press the combination of a frame, a plate-cylinder, offset-cylinder, impression-cylinder, pile-delivery, and an endless sheet-delivery chain, the said cylinders all being of the same diameter and rotational speed and being so disposed that the pile-delivery lies within a space one side of which is defined by a vertical plane that is tangent to the plate-cylinder while the rotational axes of the plate-cylinder and impression-cylinder lie in an oblique plane on one side of which lies the pile-delivery and on the other side of which is the rotational axis of the offset-cylinder, the impression-cylinder being so disposed that its periphery lies below a horizontal plane defining the upper limit of the pile-delivery space, the sheet-delivery chain being so disposed that a portion of it travels in an oblique upward direction and the latter portion of it lying immediately above the pile-delivery travels in a horizontal position, whereby the pile-delivery may be of unusual height without increasing the overall height of the press.

4. In an offset printing-press the combination of a printing-cylinder, an offset-cylinder, an impression-cylinder, a pile-delivery, and a sheet-delivery conveyor, the improvement which consists in placing the pile-delivery in a space lying immediately below that portion of the press which contains the plate-cylinder, said space however not extending beyond a vertical plane tangent to that side of the plate-cylinder that contacts with the offset-

cylinder, the offset-cylinder having its rotational axis on a different plane from that which passes through the center of the rotational axes of the plate-cylinder and impression-cylinder respectively, the pile-delivery being on one side of said last mentioned plane and the rotational axis of the offset-cylinder on the other side.

5. In an offset printing-press the combination of the usual plate-cylinder, offset-cylinder, impression-cylinder, pile-delivery, and sheet-delivery conveyor, so disposed as to bring the disposition of the rotating-axis of the offset-cylinder on that side of a plane containing the rotating-axes of the plate and impression-cylinders remote from the pile-delivery, the impression-cylinder being so placed that the lowest point in its periphery is below the plane of the topmost sheet of the pile-delivery, the sheet-delivery conveyor consisting of a chain containing an upwardly inclined portion and a horizontal portion, the said latter portion lying immediately above the stack of the delivered printed sheets and said horizontal portion being limited by a vertical plane tangent to the periphery of the plate-cylinder at the side where the same contacts with the offset-cylinder.

6. In an offset printing-press the combination of a plate-cylinder, offset-cylinder and impression-cylinder on the one hand and a pile-delivery and sheet-delivery on the other hand, so arranged as to provide a pile-delivery space capable of housing a stack of printed sheets 100 to 120 centimeters high, this being effected by disposing the rotational-axis of the offset-cylinder above a plane defined by a line passing through the rotational-axis of the plate-cylinder and impression-cylinder respectively, said cylinders as well as the offset-cylinder all being of the same diameter and traveling at the same peripheral speed, and by so positioning the impression-cylinder that the lowest point of its periphery lies below the plane which is defined by the topmost of the delivered printed sheets, the foregoing being in combination with an endless sheet-delivery chain comprising in its travel a diagonally upwardly inclined portion and a horizontal portion, said latter portion lying immediately above the stack of printed sheets and being limited by a vertical plane tangent to the periphery of the plate-cylinder at the side where the same contacts with the offset-cylinder, there thus being no working parts between the pile of delivered sheets and the plate-cylinder except the horizontal portion of said sheet-delivery chain.

In witness whereof, I have hereunto subscribed my name.

HEINRICH HENSE.
